[57] CLAIM

The ornamental design for burner cover package, as shown and described.

DESCRIPTION

FIG. 1 is a front elevational view of burner cover package showing our new design;

FIG. 2 is a rear elevational view thereof;

FIG. 3 is a right side elevational view thereof; the left side elevational view being a mirror image thereof;

FIG. 4 is a top plan view thereof;

FIG. 5 is a bottom plan view thereof;

FIG. 6 is a right side elevational view thereof; shown in an alternate position for clarity;

FIG. 7 is a sectional elevational view thereof; taken along line 7—7 of FIG. 1; and ,

FIG. 8 is a sectional elevational view thereof; taken along line 8—8 of FIG. 1.

The broken line of showing burner cover is for illustrative purpose only and forms no part of the claim.
